DESIGN FOR A DANCING TOY FIGURE

Kelly C. Sears, Rural Hall, N. C.

Application December 15, 1936, Serial No. 66,541

Term of patent 7 years

To all whom it may concern:

Be it known that I, Kelly C. Sears, a citizen of the United States, residing at Rural Hall, in the county of Forsyth and State of North Carolina, have invented a new, original, and ornamental Design for a Dancing Toy Figure, of which the following is a specification, reference being had to the accompanying drawing, forming a part thereof,

In the drawing:

Figure 1 is a front perspective view, and Figure 2 is a side elevation of a dancing toy figure embodying my design the handle being broken away for convenience in illustration.

I claim:

The ornamental design for a dancing toy figure, as shown,

KELLY C. SEARS.
